(57) **CLAIM**

The ornamental design for a glass grinder holder, as shown and described.

DESCRIPTION

FIG. 1 is a top perspective view of a glass grinder holder; FIG. 2 is a bottom perspective view thereof; FIG. 3 is a top view thereof; FIG. 4 is a bottom view thereof; and, FIG. 5 is a side view thereof.
The broken lines depict portions of the glass grinder holder in which the design is embodied that form no part of the claimed design.
